No. 853,428.

PATENTED MAY 14, 1907.

H. L. F. TREBERT.

CARBURETER.

APPLICATION FILED DEC. 14, 1904.

UNITED STATES PATENT OFFICE.

HENRY L. F. TREBERT, OF ROCHESTER, NEW YORK, ASSIGNOR TO
BROWNELL-TREBERT COMPANY, OF ROCHESTER, NEW YORK,
A CORPORATION OF NEW YORK.

CARBURETER.

No. 853,428.

Specification of Letters Patent.

Patented May 14, 1907.

Application filed December 14, 1904. Serial No. 236,786.

To all whom it may concern:

Be it known that I, HENRY L. F. TREBERT, of Rochester, in the county of Monroe and State of New York, have invented certain new and useful Improvements in Carbureters; and I do hereby declare the following to be a full, clear, and exact description of the same, reference being had to the accompanying drawings, forming a part of this specification, and to the reference-numerals marked thereon.

My present invention relates to carbureters or those devices employed for producing an explosive mixture of air and gas which is employed as a source of power for explosive or gas engines.

My invention has for its object to provide devices of this nature in which the air inlet and the passage for the liquid hydro-carbon or gas and the outlet or aspiration passage may be regulated so that by throttling the intake passage and regulating the volume of explosive mixture drawn into the engine cylinder, and also governing the amount of hydro-carbon admitted in proportion to the volume of air drawn into the carbureter the force of the explosion in the engine cylinder may be regulated to a nicety.

To these and other ends the invention consists in certain improvements and combinations of parts all as will be hereinafter more fully described, the novel features being pointed out in the claims at the end of the specification.

In the drawings: figure 1 is a transverse sectional view of a carbureter constructed in accordance with my invention. Fig. 2 is a similar view taken on the line 2^x 2^x of Fig. 1. Figs. 3 and 4 are horizontal sectional views taken on the lines 3^x 3^x and 4^x 4^x respectively, of Fig. 1, said figures illustrating the relative adjustment of the valve devices controlling the inlet and outlet passages.

Similar reference numerals in the several figures indicate similar parts.

In the present embodiment of my invention I have shown a carbureter comprising a cylindrical shell or casing 1, closed at its lower end by a bottom 2, beneath which is provided a laterally extending chamber or passage communicating with the reservoir 4, containing a float 5, mounted on a rod 6 guided in a screw cap 7, in the top of the reservoir, and a removable plug 8 inserted in the

bottom thereof. Extending transversely of the chamber 3 is a passage 9 and leading downwardly from the center thereof is the discharge passage 10 provided with a valve seat with which cooperates the conical valve head at the upper end of the stem 15. The latter is guided in an aperture in a screw plug 16 which closes the lower end of the passage 3 and is located centrally beneath the discharge aperture 10. The stem 15 is operated to open and close the inlet passage and it is automatically controlled by the movement of the float 5 the latter being connected thereto by a lever 17 arranged in the chamber 3 and pivoted at its lower end, as indicated at 18, while its opposite extremity extends between collars 19 on the rod 6.

Joined to the passage 9 is the conductor or pipe 20 through which the hydro-carbon fluid is fed, said pipe being threaded into a boss 21 and to facilitate the application of the carbureter to various makes of engines and to avoid in some instances carrying the pipe around the carbureter I provide at the opposite side of the latter a similar boss 22 which may normally be closed by a plug 23. This capability of the device to receive the supply pipe 20 at either of its sides facilitates locating the carbureter adjacent the intake valves of an engine among the parts associated therewith which are usually crowded into proximity therewith.

Extending upwardly from the bottom 2 and located centrally within the casing 1 is a tubular stem 24 forming the inlet passage through which the fluid hydro-carbon in the reservoir is permitted to flow into the vaporizing chamber. The top of the stem forming a valve seat, is preferably arranged slightly below the level of the liquid in the reservoir and is provided with an exterior shoulder 25 supporting a foraminous disk 26, secured in position by a nut 27. At the lower end of a casing 1 and beneath the disk 26 is an aperture 30 forming the air inlet passage and at the upper end of the shell or casing is the outlet or aspiration passage 31 formed in the pipe 32, which is connected with the intake passage of an explosive engine, as will be understood. In order to provide means for regulating the relative areas of the inlet and outlet passages I journal in the casing 1 a valve member in the form of a sleeve 33 provided with apertures 34 and 35, regis-

tering with the aperture 30 and the passage 31 and forming a dual valve head which may be operated to regulate equally the areas of both passages.

- 5 The sleeve is secured in the casing at its upper end by means of threads 36 and its upper end is closed by a top, having a boss 37 surrounded by a collar 38 on an operating arm or handle 39, secured rigidly to the sleeve by a screw 40. The dual valve member or sleeve 33 also carries a valve head 41 which coöperates with the valve seat on the hydro-carbon inlet and regulates the flow of the latter into the mixing chamber in amounts proportionate to the size of the air inlet and outlet passages as the partial rotation of the sleeve, necessary to close or open said passages, will cause it to be moved longitudinally slightly by means of its screw thread 36 which will cause a movement of the valve head 41 relatively to its seat. To facilitate the adjustment of the valve head to regulate the flow of hydro-carbon in the first instance, I provide the stem, 42, on which it is mounted, with screw threads 43 and extend it through a central threaded aperture in the boss 37, the upper end of which is split forming the ears 44 which may be adjusted relatively to clamp the stem in adjusted position by a bolt 45. The location of the valve seat or hydro-carbon inlet above the air inlet 34 and the foraminous support 26 between them the fluid flowing therein will be evaporated while the air passing therethrough will be subdivided into numerous small currents which will cause it to become thoroughly mixed with the hydro-carbon gas. While I have described the device as employing a fluid hydro-carbon it will be understood that it may be used equally well for combining an explosive mixture of gas and air when the former is introduced directly in a gaseous state through the inlet 24.

A carbureter embodying my invention is simple in construction and requires but few parts, the arrangement of which is such that by an adjustment of the air inlet passage the quantity of hydro-carbon which should pass to the engine cylinder is regulated proportionately.

I claim as my invention:

1. In a carbureter, the combination with a casing having air inlet and outlet passages and a hydro-carbon inlet having a valve seat, of an oscillatory member for adjusting the air inlet passage, a valve head carried thereon and coöperating with the valve seat and means for causing a longitudinal movement of the member relatively to the casing during its oscillatory movement to control the discharge area of the hydro-carbon passage.

2. In a carbureter, the combination with a casing comprising a mixing chamber and a hydro-carbon reservoir located beneath and at one side of the chamber and having a pas-

sage leading into the reservoir beneath the chamber and a valve seat in said passage, of an arm located at the bottom of the reservoir and pivoted to the casing beneath the chamber, a float connected to the one end of the arm, and a valve head supported on the latter and coöperating with the seat in the inlet passage.

3. In a carbureter, the combination with a casing comprising a mixing chamber and a hydro-carbon reservoir located beneath and at one side of the chamber and having an inwardly extending projection arranged beneath the chamber provided with a transversely extending hydro-carbon inlet, a valve seat in said passage and means at the ends of the passage for attaching a supply pipe, of an arm located at the bottom of the reservoir and pivoted to the casing beneath the chamber, a float connected to the one end of the arm, and a valve head supported on the latter and coöperating with the seat in the inlet passage.

4. In a carbureter, the combination with a casing comprising a mixing chamber and a hydro-carbon reservoir located beneath and at one side of the chamber and having a passage leading into the reservoir beneath the chamber and a valve seat in said passage, of an arm at the bottom of the reservoir pivoted at one end beneath the chamber, a float connected to the other end of the arm, a valve stem carried on the arm and coöperating with the inlet passage seat and a removable plug at the bottom of the reservoir forming a guide for the valve stem.

5. In a carbureter, the combination with a casing having air inlet and outlet passages and a hydro-carbon inlet, having a valve seat, of a rotary longitudinally movable member for adjusting the air passages and a valve head carried on said member and operated by the longitudinal movement thereof relatively to said valve seat.

6. In a carbureter, the combination with a casing having air inlet and outlet passages and a hydro-carbon inlet, having a valve seat, of a sleeve threaded in the casing and revoluble therein to adjust the air passages, and a valve head on the sleeve coöperating with said seat and carried relatively thereto by the longitudinal movement of the sleeve.

7. In a carbureter, the combination with a casing having air inlet and outlet passages and a hydro-carbon inlet extending into the casing and having a valve seat, of a rotary sleeve in the casing, and a valve head adjustable on the sleeve relatively to the valve seat, means for causing a relative longitudinal movement of the sleeve during its rotary movement.
